1

This invention relates to an improvement in deflection generators for deflecting a cathode ray beam in a cathode ray tube. More particularly, the invention relates to a system for generating the required current and voltage variations for electromagnetically deflecting a cathode ray beam.

Electromagnetic deflection of a cathode ray beam is frequently employed in apparatus using cathode ray tubes particularly where the deflection frequency remains substantially constant. Such a situation exists in television equipment where the rate of deflection and the deflection frequency of the cathode ray beam in both the horizontal and the vertical directions are maintained substantially fixed. For electromagnetically deflecting a cathode ray beam where the rate of deflection is uniform, it is necessary to cause the flux to alter its density in a linear manner. Accordingly, this requires a linear change in the amount of current that is permitted to flow through the winding of the electromagnetic deflection yoke since the flux produced by the yoke is substantially in direct proportion to the amount of current in the winding of the yoke throughout its normal range of current variation. The yoke is highly inductive, and as a result the voltage applied to the terminals of the yoke winding must be maintained substantially throughout the deflection interval. Under these conditions, the rate of change of the current and the corresponding rate of change of flux will be uniform and constant.

Various circuit arrangements have been devised for electromagnetically deflecting a cathode ray beam, and most circuits have, in the past, included blocking oscillators for controlling a discharge tube to produce a desired voltage variation which, in turn, is applied to an output deflection tube for producing the desired current variations. Such deflection systems often become rather involved and usually entail the use of a considerable number of tubes. Furthermore, previous systems, in which a lesser number of tubes are used, are not wholly satisfactory in that the operating frequency, the amplitude of deflection and the linearity of deflection are not unrelated, thus making it necessary to adjust all three of these parameters should it become necessary to adjust any one.

Conventional electromagnetic deflection circuits are also frequently objectionable from the standpoint of stability, and require regularly recurring synchronizing impulses to prevent erratic operation of the deflection generator. Fur-

thermore, previously used deflection systems could not readily be controlled in frequency by the application of a relatively low potential to the system thereby making it difficult to apply automatic frequency control potentials to the deflection generator.

The present invention comprises a simple and reliable system for producing current variations for electromagnetically deflecting a cathode ray beam in a cathode ray tube. The present invention includes essentially only two tubes, one of which operates as an oscillator and the other operates as the usual damping or inverted tube. In the present invention both the amplitude of deflection and the frequency or rate of deflection may be independently controlled without in any way affecting the other. Furthermore, the frequency of operation of the present invention may also be controlled by the application of a relatively small control potential so that automatic frequency control may readily be applied to the present invention. The system shown and described herein is also responsive to synchronizing impulses of relatively low amplitude, thus making it possible to synchronize the frequency of operation of the deflection generator from a series of available or received synchronizing impulses.

One purpose of the present invention resides in the provision of a deflecting generator for electromagnetically deflecting the cathode ray beam, the generator being simple in operation, and involving a relatively small number of essential elements.

Another purpose of the present invention resides in the provision of an electromagnetic deflection generator in which provisions are made for adjusting both the amplitude of deflection and the frequency of deflection, each of these adjustments being entirely independent of the other.

Still another purpose of the present invention resides in the provision of an electromagnetic deflection generator which is responsive to synchronizing impulses of relatively low intensity.

A still further purpose of the present invention resides in the provision of an electromagnetic deflection generator in which the frequency of operation of the generator may be controlled within prescribed limits by the application of a relatively low direct current potential to the oscillator tube of the deflection generator.

Still another purpose of the present invention resides in the provision of an electromagnetic deflection generator in which the frequency of operation may be maintained constant with prac-

tically no deviation from the prescribed frequency of operation through the use of a simple tuned circuit associated with the oscillator tube.

A further purpose of the present invention resides in the provision of a simple and efficient electromagnetic deflection system which requires a relatively small amount of driving power.

Various other purposes and advantages of the present invention will become more apparent to those skilled in the art from the following detailed description particularly when considered in connection with the drawings wherein like reference numbers represent like parts and wherein;

Figure 1 represents one form of the present invention;

Figures 2 and 3 show curves representing the current and voltage variations occurring at certain points in the deflection system;

Figure 4 shows a curve relating operating frequency to applied control voltage; and,

Figure 5 shows a modified form of the present invention.

Referring now to the drawings and particularly to Figure 1, there is shown an oscillator tube 10 and an inverted or damping tube 12. Oscillator tube 10 includes at least a cathode 12, a control electrode 14, a screen grid electrode 16 and an anode 18. This tube should preferably be in the form of a beam power amplifier tube of a type similar to the 6L6 tube and should be capable of dissipating considerable power to a screen grid electrode. The damping tube 12 also includes a cathode 20, a control electrode 22, a screen grid electrode 24 and an anode 26. This tube should also preferably be in the form of a beam power tube.

The deflection generator also includes transformer 30 which comprises three windings 32, 34 and 36. The winding 32 may be considered as a secondary winding since the terminals 38 of this winding are connected to the deflection yoke (not shown). The winding 36 is included in the plate or anode circuit of tube 10 and one end of the winding 36 is connected to the anode 18 of tube 10 while the other end of the winding 36 is connected to terminal 48 (to which a source of positive potential is applied) by way of the amplitude control resistor 42. A condenser 44 is connected between this side of the winding 36 and a point of fixed potential or ground. The winding 34 is for feed-back purposes and applies the necessary blocking potential to the screen grid electrode 16 of the oscillator tube 10. One end of the winding 34 is therefore connected to a screen grid electrode 16 of tube 10 while the other end of the winding 34 is connected to a point of fixed potential or ground by way of a low frequency control resistor 46. The negative terminal of the source of potential is applied to terminal 48 which is connected to the point of fixed potential or ground.

In order that current may flow through the plate winding 36, the cathode 12 of tube 10 is connected to ground by way of cathode resistor 58 while, in the form of the invention shown in Figure 1, the control electrode 14 of the oscillator tube 10 may be connected to ground by way of grid resistor 52.

The plate or anode of the damping tube 12, which is essential for linearizing the deflection of the cathode ray beam, is connected directly to the source of positive potential while the cathode 20 of the damping tube is connected directly to the anode 18 of tube 10. The control electrode of tube 12 is connected to the anode 18

and to the cathode 20 by two series networks each including a parallel connected resistance and condenser. The parallel connected resistance 54 and condenser 56, together with the parallel connected resistance 58 of the condenser 59, control the potential variations that are to affect the control electrode 22 for controlling the impedance of the damping tube 12 in a manner such as to compensate for the lack of linearity in the characteristics in the oscillator tube 10. The screen grid electrode 24 of the damping tube 12 is connected to a movable contact of a potentiometer 62 and the resistance element of the potentiometer is connected between the positive and negative terminals of the potential source. Accordingly, by adjusting the movable contact along the resistance element of the potentiometer 62, the positive potential applied to a screen grid electrode 24 is controllable. A condenser 64 is connected between the screen grid electrode 24 and a point of fixed potential.

In describing the operation of the circuit arrangement shown in Figure 1, it should first be pointed out that the transformer 30 operates both as the oscillation transformer and the output transformer. Furthermore, the oscillator tube 10 operates as an electron switch for connecting the yoke inductance through the plate transformer winding 36 to the applied source of potential. When the oscillator tube 10 is in a conducting condition electronic current flows from ground through the cathode resistor 58, from cathode 12 to anode 18, through the plate winding 36, and to the source of positive potential 40. This current increases according to the parameters of the circuit and in a substantially linear manner until the potential drop across resistance 46 which is applied to the screen grid electrode 16 of the oscillator is sufficient to block the oscillator tube from operation.

It will be observed that the feed-back winding 34 responds to the flow of current through the plate winding 36. At the instant that the oscillator tube 10 is blocked, energy stored in the deflection yoke, by reason of its inductance, will discharge in an oscillatory fashion through its distributed capacity until the potential of the lower end of the plate winding 36 becomes negative with respect to the opposite end of that winding. At this time, a negative potential is applied to the cathode 20 of tube 12 and a positive potential is applied to the anode of that tube.

As soon as this condition occurs, the damping tube 12 begins to conduct and the electronic current flow during the interval is from the cathode 20 to the plate 26 of tube 12, through the amplitude control resistance 42, the plate winding 36, and back to the cathode 20. The wave form of the current which flows during the interval of conductivity of the damping tube 12 is dependent upon a value of the resistances 54 and 58 and capacitances 56 and 59 included in the circuit of the control electrode 22. Furthermore, the intensity of the current which flows through the damping tube 12 may be controlled by adjusting the potential of the screen grid electrode 24 of that tube by means of the potentiometer 62. This affords a means for controlling or further adjusting the linearity of deflection. The flow of current through the damping tube 12, aside from increasing the efficiency of the system, also materially improves the linearity of deflection by compensating for the non-linearity of the oscillator tube, provided the circuit parameters as

sociated with the control electrode 22 are properly chosen.

For a predetermined time after blocking of the oscillator tube, the current passed by the damping tube flows through the plate winding 36. This current diminishes and finally the electronic current in the plate winding 36 reverses since the current supplied by the cathode 12 of the oscillator tube 10 exceeds the amount of current passed by the damping tube 12. During a portion of the operating cycle, electronic current flows through both the oscillating tube and the damping tube with the current through the oscillating tube increasing somewhat linearly to a predetermined maximum. At the end of the cycle, the oscillating tube 10 is again blocked by the application of a negative impulse of potential to the screen grid 16 of that tube and the cycle begins again.

This cyclical operation of the circuit continues and its frequency may be adjusted by altering the value of the resistance 46. A decrease in the size of this resistance is effective to decrease the frequency of operation while an increase in the resistance 46 increases the frequency of operation. This cyclic operation and the resulting generation of deflection currents are continued even in the absence of any synchronizing impulses applied to the control electrode 14.

Reference is now made to Figure 2 where the cathode current passed by the oscillator tube 10 and the plate current of the damping tube 12 are related. The current through the oscillator tube is represented by the curve 70 while the damping tube current is represented by curve 72. The differential current of these two tubes is represented by the curve 74 which is, in fact, the current which flows through the winding 36. It will be observed that the wave form of neither the oscillator nor the damping tube is linear yet the net current of these two tubes is quite linear and it is this net current that is effective, through the use of the transformer, in determining the linearity of deflection of the cathode ray beam. Figure 3 shows the voltage that is present at the screen grid electrode 16 of the oscillator tube 10. It will be observed that this voltage is positive (approximately 100 volts) during the entire working cycle of the oscillator tube and that a relatively high negative potential is present in the instant that the oscillator is blocked. This negative potential may be as high as 1,000 volts or more and it is for this reason that the screen grid electrode should be capable of dissipating considerable energy. If sufficient energy cannot be dissipated by the screen, the temperature produced at the screen electrode during the working cycle may be sufficient to render the screen grid thermionically emissive at the time it is driven to such a negative potential. Electron emission from the screen grid during this negative blocking interval is undesirable and if present will tend to increase the frequency of operation.

Since the feedback voltage for controlling the oscillator tube 10 is applied to the screen grid electrode 16, the control electrode 14 is available for synchronizing purposes. Due to the high transconductance of the control electrode 14 it has been found that a very small synchronizing signal or impulse is effective to synchronize or lock the oscillator. Synchronizing signals of low intensity and of negative polarity may, therefore, be applied to terminal 76 in order to synchronize the deflection generator with a source

of recurring impulses. Under these conditions it is desirable that the natural period of oscillation be at a frequency that is slightly lower than the frequency of occurrence of the synchronizing signals. The natural frequency of operation may be set at this slightly lower frequency by means of the resistance 46.

It has also been found that the frequency of operation may be controlled over a predetermined range by applying a steady direct current potential to the control electrode 14 of the oscillator tube 10. Figure 4 shows a curve representing the relationship between the frequency of operation and the potential applied to the control electrode. If, for example, the frequency control resistance 46 chosen such that the oscillator operates at approximately 16,000 cycles per second, then this frequency of operation may be increased or decreased within prescribed limits by the application of an appropriate direct current potential to the control electrode 14. This variation in frequency is of the order of about 3% for each one volt change in the control electrode potential. The potential of the control electrode 14 should not, however, be made more than about 3.5 volts negative since the application of a negative potential in excess thereof tends to render the deflection generator unstable. A variation in potential from approximately 3 volts negative to 2 or more volts positive is entirely feasible and the resulting change in frequency is well within the range necessary to permit the use of automatic frequency control circuits, if desired. Circuit arrangements for producing the desired automatic frequency control potentials for controlling the operating frequency of the deflection generator are shown and described, for example, in the patent to Guanella, No. 2,231,998, issued on February 18, 1941, and in the patent to Wendt, No. 2,339,536, issued on January 18, 1944.

As pointed out above, the cathode of the damping tube 12 may be driven several thousand volts above ground potential during the return time interval, and if the heater for this tube is operated at ground potential the tube may break down between cathode and heater. In order to prevent such a failure of the damping tube 12 it is preferable to float the heater above ground either by use of a separate transformer with low capacity to ground or by connecting chokes in the heater circuit between the heater and the transformer. In this connection the amount of added capacity between cathode and ground should be maintained at a minimum since such capacity electrically appears directly across the output transformer 30 and will affect or extend the return time which should be kept short, especially if the deflection generator is to be used for television purposes. The use of a floating transformer or the use of chokes is well within the province of one skilled in the art. However, such expediences are not always desirable and a circuit arrangement such as shown in Figure 5, representing a modification of the subject invention, may be employed whereby the cathode of the damping tube is operated at or near ground potential. In general, this circuit arrangement is somewhat similar to the circuit shown in Figure 1 except that the damping tube 12 of Figure 5 is connected across the grid or feed-back winding 34 instead of across the plate winding 36 as in Figure 1. Since the energy contained in the deflection yoke is reflected into the transformer 30, this energy may be controlled by connecting

the damping tube 12 across either of the windings. In Figure 5, the winding 36 carries the plate current of the oscillator tube only while the current through the damping tube 12 is permitted to flow through the feed-back winding 34. The differential, or net current, of the two tubes is still, however, effective to control the rate of deflection since both these windings 36 and 34 are associated on the same transformer 30 and are electromagnetically coupled to the secondary winding 32 to which the deflection yoke is connected.

As a further means for accurately determining or controlling the frequency of operation of the deflection generator a tuned circuit such as the inductance 80 and a capacitance 82 may be employed and connected in circuit with the control electrode 14 of the oscillator tube 10 as shown in Figure 5. If the coarse frequency control, including the resistance 46, is adjusted so that the oscillator will operate at near the resonant frequency of the inductance 80 and the condenser 82, then the deflection generator will function at the resonant frequency of this circuit. The accuracy with which the value of the resistance 46 must be set is determined by the Q of the resonant circuit. Although this resonant circuit is disclosed as applied to the circuit shown of Figure 5, such an arrangement is also applicable to the circuit shown in Figure 1 and synchronizing impulses or direct current potentials may be utilized to control the frequency of operation of the circuit arrangement shown in Figure 5.

The tuned circuit including inductance 80 and capacitance 82 may also be used in conjunction with synchronizing impulses or automatic frequency control potentials. Where it is desired to so control or "lock" the frequency of operation of the deflection generator, the tuned circuit may be isolated from ground insofar as direct current potentials are concerned by the condenser 84 which is relatively large, as compared with the condenser 82. Automatic frequency control potentials or synchronizing impulses may then be applied between ground and the terminal 86.

The circuit shown in Figure 5 is actually as effective for producing linear deflections of a cathode ray beam as is the circuit of Figure 1 and similarly the amplitude or size control and the frequency control of the generator are independently adjusted. The circuit of Figure 5 may, however, produce slight oscillatory ripples in the return trace, but this is not objectionable in most instances unless the pulse that occurs during this interval is to be used in associated circuits.

Through the use of either of the systems shown in Figure 1 or Figure 5 it is evident that a simple and effective deflection generator has been produced which may be used for electromagnetically deflecting a cathode ray beam and in which the deflection of the beam is substantially linear throughout its entire deflection stroke. As pointed out above, the circuit arrangements shown and described herein have the advantage that the amplitude of deflection, the frequency of operation, and the linearity of deflection may be independently controlled. Furthermore the system may be readily locked in operation at a desired frequency through the use of applied synchronizing impulses or it may be stabilized or controlled by the application of a direct current potential. A tuned resonant circuit with or without the inclusion of a crystal may also be used for

definitely fixing the frequency of operation. If the tuned circuit, when used, is not too sharply resonant, automatic frequency control potentials or synchronizing impulses may also be used to control the frequency over a range of several percent as shown in Figure 5.

It is to be understood that the present circuit arrangements, although developed primarily for television use, may be well applied to any electrical equipment where electromagnetic deflection of a cathode ray beam is employed.

I claim:

1. An oscillator for producing current variations of substantially sawtooth waveform comprising an electron discharge tube having at least a cathode, a control electrode, a screen electrode and an anode, a first inductance connected between the anode of said tube and the positive terminal of a source of potential, the negative terminal of which is connected to a point of fixed potential, means for connecting the cathode of said discharge tube to the point of fixed potential, a second inductance connected between the screen electrode and the point of fixed potential, said first and second inductances being electromagnetically coupled, a damping tube connected across said first inductance, and means for applying a variable direct current potential to the control electrode of the electron discharge tube to

20 control the operating frequency of the oscillator.

2. An oscillator for producing current variations of substantially sawtooth waveform comprising an oscillator tube having at least a cathode, a control electrode, a screen electrode and an anode, a first and a second inductance element electromagnetically coupled to each other, means for connecting the first inductance between the anode of said oscillator tube and a source of positive potential, means for connecting said second inductance between the screen electrode and a point of fixed potential, means for connecting the cathode of said oscillator tube to the point of fixed potential, a damping tube connected across said second inductance, means to control 35 the transconductance of said damping tube, and means for applying a variable direct current potential to the control electrode of said oscillator to control the frequency of operation of the oscillator.

3. An oscillator for producing current variations of substantially sawtooth waveform comprising an oscillator tube having at least a cathode, a control electrode, a screen electrode and an anode, a first inductance connected between the anode and the positive terminal of a source of potential, means for connecting the cathode to the negative terminal of the source of potential, a second inductance, means for connecting said second inductance between said screen electrode and the negative terminal of the source of potential, said first and second inductances being electromagnetically coupled, a damping tube connected across one of said inductances, and means whereby low potential synchronizing impulses of negative polarity may be applied to the control electrode of said tube to control the frequency of operation of the deflection tube.

4. An oscillator for producing current variations of substantially sawtooth waveform comprising an electron discharge tube having at least a cathode, a control electrode, a screen electrode and an anode, a first inductance connected between the anode of said tube and the positive terminal of a source of potential, the negative ter-

70

inal of which is connected to a point of fixed potential, means for connecting the cathode of said discharge tube to the point of fixed potential, a second inductance connected between the screen electrode and the point of fixed potential, said first and second inductances being electro-magnetically coupled, a damping tube connected across said first inductance, means for controlling the conductivity of said damping tube, and means for applying synchronizing impulses to the control electrode of the electron discharge tube to control the operating frequency of the oscillator.

5. An oscillator for producing current variations of substantially sawtooth waveform comprising an oscillator tube having at least a cathode, a control electrode, a screen electrode and an anode, first and second inductance elements electromagnetically coupled to each other, means for connecting the first inductance between the anode of said oscillator tube and a source of positive potential, means for connecting said second inductance between the screen electrode and a point of fixed potential, means for connecting the cathode of said oscillator tube to the point of fixed potential, a damping tube connected across said second inductance, means to control the transconductance of said damping tube, and means for applying synchronizing impulses to the control electrode of said oscillator to control the frequency of operation of the oscillator.

6. An oscillator for producing current variations of substantially sawtooth waveform comprising an oscillator tube having at least a cathode, a control electrode, a screen electrode and an anode, a first inductance connected between the anode of said tube and the positive terminal of a source of potential, means for connecting the cathode of said tube to the negative terminal of the source of potential, a second inductance, electromagnetically coupled to said first inductance, connected between the screen electrode and the source of negative potential, and a resonant circuit connected between the control electrode and the cathode of said tube to maintain the frequency of operation of the oscillator relatively fixed.

7. An oscillator for producing current variations of substantially sawtooth waveform comprising an electron discharge tube having at least a cathode, a control electrode, a screen electrode and an anode, a first inductance connected between the anode of said tube and the positive terminal of a source of potential, the negative terminal of which is connected to a point of fixed potential, means for connecting the cathode of said discharge tube to the point of fixed potential, a second inductance connected between the screen electrode and the point of fixed potential, said first and second inductances being electromagnetically coupled, a damping tube connected across said first inductance, means for controlling the conductivity of said damping tube, and a circuit connected between the control electrode and the point of fixed potential to control the operating frequency of the oscillator.

8. An oscillator for producing current variations of substantially sawtooth waveform comprising an oscillator tube having at least a cathode, a control electrode, a screen electrode and an anode, first and second inductance elements electromagnetically coupled to each other, means for connecting the first inductance between the anode of said oscillator tube and a source of positive potential, means for connecting said second inductance between the screen electrode and a point

of fixed potential, means for connecting the cathode of said oscillator tube to the point of fixed potential, a damping tube connected across said second inductance, means to control the transconductance of said damping tube, and a resonant circuit connected between a control electrode of the oscillator tube and a point of fixed potential to stabilize the frequency of operation of the oscillator.

10 9. A deflection generator for producing current variations of substantially sawtooth waveform comprising an oscillator tube having a cathode, a control electrode, a screen electrode and an anode, means for connecting the cathode to a point of fixed potential, means including a first inductance for normally maintaining the anode positive with respect to the cathode, means including a second inductance, electromagnetically coupled to said first inductance, for connecting the screen electrode to the point of fixed potential, a tuned circuit coupled between the control electrode and the cathode of said tube, and means whereby a control potential may be applied to the control electrode of said tube to control, within predetermined limits, the operating frequency of the deflection generator.

10. An oscillator for producing current variations of substantially sawtooth waveform comprising an oscillator tube having at least a cathode, a control electrode, a screen electrode and an anode, a first inductance connected between the anode of said tube and the positive terminal of a source of potential, means for connecting the cathode of said tube to the negative terminal of the source of potential, a second inductance, electromagnetically associated with said first inductance, connected between the screen electrode and the source of negative potential, a tuned circuit coupled between the control electrode and the cathode of said tube to maintain the frequency of operation of the oscillator relatively fixed, and means for altering the direct current potential of the control electrode of the oscillator tube to alter the frequency of operation of the oscillator within a relatively narrow range included within the resonant frequency band of the tuned circuit.

11. A deflection generator for producing current variations of substantially sawtooth wave-form comprising an oscillator tube having at least a cathode, a control electrode, a screen electrode and an anode, a first inductance connected between the anode and the positive terminal of a source of potential, means for connecting the cathode to the negative terminal of the source of potential, a second inductance, means for connecting said second inductance between said screen electrode and the negative terminal of the source of potential, said first and second inductances being electromagnetically coupled, a resonant circuit coupled between the control electrode and the cathode of said tube to stabilize the frequency of operation of the deflection generator, and means whereby synchronizing impulses may be applied to the control electrode of said tube to further control the frequency of operation of the deflection tube.

12. An oscillator for producing current variations of substantially sawtooth waveform comprising an oscillator tube having at least a cathode, a control electrode, a screen electrode and an anode, a first inductance connected between the anode of said tube and the positive terminal of a source of potential, means for connecting the cathode of said tube to the negative terminal of

11

the source of potential, a second inductance, electromagnetically associated with said first inductance, connected between the screen electrode and the source of negative potential, a resonant circuit coupled between the control electrode and the cathode of said tube to maintain the frequency of operation of the oscillator relatively fixed, and means adapted for applying synchronizing impulses to the control electrode of the oscillator tube to further control the frequency of operation of the oscillator.
